(57) **CLAIM**

The ornamental design for a vehicle hull, as shown and described.

DESCRIPTION

FIG. 1 is a front right perspective view of a vehicle hull according to the present invention;

FIG. 2 is a front left perspective view of the vehicle hull shown in FIG. 1;

FIG. 3 is a rear left perspective view thereof;

FIG. 4 is a rear right perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof; and,

FIG. 11 is a top view of the vehicle hull shown in FIG. 1-10, but with the hull mounted on a vehicle, and the rest of the vehicle shown in de-emphasized and half-tone portions so as to illustrate environmental structure. These portions form no part of the claimed invention. More particularly, in FIG. 11, the inventive vehicle hull is shown within the broken line, and the elements shown outside of the broken line form no part of the claimed invention, but are instead included to show environmental aspects thereof.
